UNITED STATES PATENT OFFICE

2,484,350

OBSTRUCTION LIGHTING STRUCTURE

Clyde K. Lamb, Cleveland, Ohio, assignor, by
mesne assignments, to Lamb & Chapin, Incorporated, Cleveland, Ohio, a corporation of Ohio

Application May 21, 1946, Serial No. 671,320

8 Claims. (Cl. 240—2)

1

My invention relates to obstruction lighting structures and relates more particularly to the provision of a permanent lighting structure adapted to circumscribe a chimney or stack and carrying lights which are visible both from the ground and from the air and which are particularly useful in warning approaching aircraft of the presence of such stack or chimney structures.

My invention further relates to obstruction lighting structures of the type described combining the provision of a permanent lighting structure with a guard rail structure adapted to protect workmen engaged in servicing the obstruction lights carried thereby.

Another object of my invention relates further to the provision of obstruction lighting structures of the type described wherein the lights may be easily serviced.

Another object of my invention is to provide obstruction lighting structures of the type referred to incorporating therein means whereby said lights may be easily cleaned by remote control, preferably located at ground level.

This application is a continuation in part of my co-pending application Ser. No. 579,292, filed February 22, 1945.

Other objects of my invention and the invention itself will become increasingly apparent by reference to the following description of embodiments of my invention and to the drawings thereof, in which drawings:

Fig. 1 is a side elevational view of the lighting structure of my invention;

Fig. 2 is a top plan view partially in section of the obstruction lighting structure of Fig. 1;

Fig. 3 is a side elevational view of the embodiment of Figs. 1 and 2;

Fig. 4 is a view taken from the line 4—4 of Fig. 3;

Fig. 5 is a top plan view partially in section, certain portions being broken away so that other parts may be more fully illustrated, of a modification of the lighting structure of my invention as applied to a circular stack;

Fig. 6 is a view similar to that of Fig. 1 of the modification of Fig. 5; and

Fig. 7 is an enlarged view taken on the line 7—7 of Fig. 6.

Referring now to the drawings, in all of which like parts are designated by like reference characters, at 10 I have indicated generally the obstruction lighting structure of my invention, this lighting structure consisting of three light-carrying mountings, A, B and C, and reinforcing mem-

2

bers, D. It will be obvious that, according to the size of the stack or chimney upon which such lighting structure is carried, the number of lighting structures warning of the presence of such air obstruction to aircraft and the like, may be varied and hence the number of reinforcing members may be increased. Such reinforcing members may further be eliminated, if desired.

In normal scaffold construction employed in creating a staging for work on chimneys, etc., a pair of metallic bands 3 and 4 are adapted to be telescoped about the entire circumference of the stack or chimney 5, said bands being spaced a substantial distance apart and being disposed about the entire circumference of the stack or chimney 5 at the height at which the structure is to be positioned. A preferred spacing between the bands in my invention is about 40". Each of the metallic bands 3 and 4 are preferably further, as best shown in Fig. 1, composed of a plurality of similar metal bands secured together by couplings which are bolted together wherefore the bands are tightly secured to the chimney or stack structure and the light-carrying devices, A, B and C, and the reinforcing members D are rigidly secured thereto.

It will be noted that a plurality of U-shaped step members 30 are disposed over the band 4, said steps being provided with downwardly extending portions 31 disposed between the bands 4 and the chimney structure, a hooked end portion 32 of each locking the step to the band and preventing the disengagement of the step therefrom.

35 A plurality of hand grip members 30', aligned with said step and having downwardly extending portions 31', ending in upwardly disposed end hook portions 32' and similarly formed to the step members 30, are disposed between the upper band 3 and the chimney or stack. These hand grip and step members are similar to those described and claimed in Patent No. 2,358,014 of this applicant and in my co-pending application.

45 The improved obstruction lighting structure of my present invention is preferably embodied in a combined back rail and loop structure which is formed in the following manner:

A plurality of loops 10 are disposed about the work structure upon which the lamps A, B and C are carried, formed similarly to the reinforcing members D being preferably tubular and generally cylindrical in form and comprise a pair of legs 11 and 12 and a yoke 13, the leg 11 initiating in a hooked end portion 15 curved over the band 3 disposed around the circumference of the chim-

ney, a portion of said leg adjacent said curved end portion being telescoped between the said band and the chimney and a lower end portion of said leg 11 being telescoped between the band 4 and said chimney, the main portion of the leg being disposed substantially vertically and flush with the sides of the chimney. The yoke 13 is disposed at substantially right angles to the chimney structure and to the leg 11 and extends outwardly from the chimney, the leg 12 extending at right angles thereto and maintained thereby in spaced and parallel relation to the leg 11. The leg 12, similarly to the leg 11, is disposed with an upper curved portion 16 which is hooked about a conduit 17, outwardly spaced from the cylindrical stack by said loops, the said conduit forming an outer cylindrical band and guard rail structure encompassing said stack and adapted, in the forms of my invention shown herein, to be disposed beneath the cross members 24 supporting the light fixtures A, B and C. Said lights receive current through a cable 50 carried by the conduit 51 disposed about the cylindrical band 4 and the cable 50 is telescoped within the tubular yoke 13 and the tubular leg 12, passing through the mounting 24 to the lamp connections.

An air conduit 60, which is also disposed adjacent the ladder passes through the yoke 13 and leg 12, travels across the support 24 and branches off into a pair of narrow tubes 70 preferably of copper, a pair of each of these being placed about each of the lamps and spaced therefrom and being bowed in the manner shown in my aforementioned patent and application. The air conduit proceeds from the lamp structure A to structures B and C through the conduit 17 to clean the lamps thereat.

The reinforcing members D are similarly formed to the lamp carrying loop structures 10 and are disposed about the circumference of the chimney or stack at spaced intervals, the hooked end portions thereof being secured respectively to the band 3 and the conduit 17. These loop portions and reinforcing members further serve as staging and back rail members since they maintain the conduit 70 in spaced relation from the chimney and in the form of my invention shown in Figs. 1 to 4 inclusive, the step members 30 and a hinged step 40 adjacent the ladder 60 and lamp structure A may be utilized as a platform upon which the workmen may work about the chimney to repair or replace the lamps. It will be noted that the step 40 hereinbefore referred to is hinged, as at 39, to the leg 11 and rests upon a step member 38 formed in the manner of the step members 30 when said step 40 is in its downward or operative position. Said platform step 40 is preferably grilled as best shown in Fig. 2 and has a pair of diagonal downwardly extending members 42 journaled about the yoke 13 which act as additional reinforcing members to carry the weight of said grilled step when in its operative position. A catch 44 which is secured to an upper portion of the leg 11 is adapted to lock the step 40 in an inoperative position in order that the workmen may ascend the chimney without interference.

In the form of my invention shown in Figs. 5, 6 and 7, in lieu of the steps 30, triangular brackets 100 support U-shaped loops 101 similar in form to those shown at 12 and having a pair of oppositely disposed parallel leg portions 102 and 103 and a yoke portion 104 which is provided with a plurality of grooves 105 through which rods 106 are adapted to pass, said rods being circular in

cross section and forming a continuous platform together with the grilled step 40 for the workmen to pass around the chimney and from one set of obstruction lighting fixtures to the other.

At the ends of said rods adjacent the grilled step, the rods are supported by the bracket and platform supporting horizontally disposed portion is disposed extending inwardly from the outer end of the diagonal member 107 to the upright member 108 of the bracket and said portion is provided with corrugations or grooves similar to grooves 105 provided in the web 104 and the said yoke, and the upwardly extending legs 102 and 103 are dispensed with. At these ends of the rods as well as at the loop intersecting areas, a band 109 is clamped over the rods 106 and bolted by means of bolts 110-110 to the yoke portion 104 or to the horizontal portion substituted therefor in order to maintain the rods 106 within the corrugations 105 or the like.

Although, I have described my invention in connection with certain preferred embodiments thereof, I am aware that numerous and extensive departures may be made therefrom without, however, departing from the spirit of my invention and the scope of the appended claims.

I claim:

1. An obstruction lighting structure comprising a substantially U-shaped member, said member being secured to a cylindrical upright work surface and having an upwardly extending leg portion, an outwardly extending yoke portion, and an upwardly extending leg portion spaced from said first mentioned leg portion, a cylindrical band adapted to be secured to said outwardly spaced leg portion adjacent an upper portion thereof, a platform associated with said cylindrical upright work surface and adapted to be disposed adjacent the yoke of said U-shaped member whereby a platform is provided for a workman, said cylindrical band acting as a guard rail to protect said workman.

2. An obstruction lighting structure comprising a substantially U-shaped member, said member being secured to a cylindrical upright work surface and having an upwardly extending leg portion, an outwardly extending yoke portion, and an upwardly extending leg portion spaced from said first mentioned leg portion, a cylindrical band adapted to be secured to said outwardly spaced leg portion adjacent an upper portion thereof, a platform associated with said cylindrical upright work surface and adapted to be disposed adjacent the yoke of said U-shaped member whereby a platform is provided for a workman, said cylindrical band acting as a guard rail to protect said workman, said platform adapted to be locked in closely adjacent contact with said cylindrical work surface when in inoperative use.

3. An obstruction lighting structure comprising a substantially U-shaped member, said member being secured to a cylindrical upright work surface and having an upwardly extending leg portion, and outwardly extending yoke portion, and an upwardly extending leg portion spaced from said first mentioned leg portion, a cylindrical band adapted to be secured to said outwardly spaced leg portion adjacent an upper portion thereof, a platform associated with said cylindrical upright work surface and adapted to be disposed adjacent the yoke of said U-shaped member whereby a platform is provided for a workman, said cylindrical band acting as a guard rail to protect said workman, a pair of diagonal brace

members being journaled about said yoke and serving as support members for said platform.

4. An obstruction lighting structure for a substantially cylindrical work surface such as a chimney or the like, said work structure having a pair of cylindrical bands telescoped thereover, said bands being disposed about said cylindrical structure and in spaced relation relative to each other, a plurality of substantially U-shaped members adapted to be telescoped between said cylindrical bands and said cylindrical work structure and rigidly secured thereto, said members each comprising a yoke portion disposed outwardly from said cylindrical work surface, each said yoke terminating in an upwardly extending leg disposed substantially parallel and in spaced relation to that portion of said member disposed adjacent the work surface, each said leg supporting lighting fixtures, a cylindrical guard rail member associated with the upper portion of each of said legs and circumscribing a substantial portion of the cylindrical work surface, tread members disposed adjacent the yoke of each of said members forming a work platform for the workman.

5. An obstruction lighting structure for a substantially cylindrical work surface such as a chimney or the like, said work structure having a pair of cylindrical bands telescoped thereover, said bands being disposed about said cylindrical structure and in spaced relation relative to each other, a plurality of substantially U-shaped members adapted to be telescoped between said cylindrical bands and said cylindrical work structure and rigidly secured thereto, said members each comprising a yoke portion disposed outwardly from said cylindrical work surface, each said yoke terminating in an upwardly extending leg disposed substantially parallel and in spaced relation

to that portion of said member disposed adjacent the work surface, each said leg supporting lighting fixtures, a cylindrical guard rail member associated with the upper portion of each of said legs and circumscribing a substantial portion of the cylindrical work surface, a plurality of arcuately shaped platform forming members adapted to overlie the yoke portions and to form a continuous platform for the workman, said platform circumscribing a substantial portion of the cylindrical work surface.

5 6. An obstruction lighting structure as claimed in claim 5, each said yoke being provided with a series of corrugations through which said platform forming members are adapted to pass.

10 7. An obstruction lighting structure as claimed in claim 6 having a plurality of bands, each band adapted to be clamped over a portion of said yoke portion and said platform forming members disposed in the corrugations of said yoke whereby said platform is rigidly secured to said U-shaped members.

15 8. An obstruction lighting structure as set forth in claim 5, each said yoke portion forming a part 20 of a triangular bracket portion.
